UNITED STATES PATENT OFFICE.

LOUIS STEINBERGER, OF BROOKLYN, NEW YORK.

INSULATING-KNOB.

1,348,249.

Specification of Letters Patent.

Patented Aug. 3, 1920.

Application filed January 17, 1918. Serial No. 212,336.

To all whom it may concern:

Be it known that I, LOUIS STEINBERGER, a citizen of the United States, and a resident of the borough of Brooklyn, county of 5 Kings, city and State of New York, have invented certain new and useful Improvements in Insulating-Knobs, of which the following is a specification.

My invention is particularly adapted for 10 use in radio installations, though its use is not limited to any particular form or manner of hand operated key for making and breaking electrical contacts.

One of the objects of my invention is to so 15 fashion and conduct the finger knobs of telegraph keys that the operator thereof will not receive electrical shocks.

Another object is to provide a protective 20 insulating shield upon a key knob between the metal lever of the key and the portion 25 of the knob upon which the hand of the operator is placed.

Another object is to so form the above 30 mentioned protective insulating shield so that the operator will be protected from electrical shocks even though a current of high frequency be sent through the apparatus.

Another object is to so utilize the particular 35 insulating shield as to cause it to function also as a finger or hand rest for the operator.

Other objects will appear from the following description and claims.

Referring to the drawings:

Figure 1 is an elevation of my improved 35 insulating knob with a protective insulating shield secured to a key lever, the portion of the key lever at the point of connection being in section.

Fig. 2 is an enlarged vertical section of 40 a knob embodying my invention illustrating in elevation a means for attaching the same to the metal lever.

Fig. 3 is a plan of my improved knob, looking at the underside of the protective 45 shield.

Referring to the drawings, 10 is a finger knob provided with a flanged upper finger portion 11 of the usual form, from which projects a stem or shank 12 for attachment 50 to the key operated lever L. Projecting radially from the stem 12 at a point substantially midway thereof is a flange or shield 13 of greater diameter than the diameter of the finger portion of the knob. This flange 55 or shield is preferably grooved or corrugated on the lower surface thereof by form-

ing a series of alternately disposed grooves 16 and ridges 17 as shown, so that a greater insulating surface will be provided for the creepage of the current and thereby more 60 effectually insulate and protect the operator when currents of high frequencies are used.

Many means may be employed for securing the knob to the metal key, one of which 65 is illustrated and which I find to be very convenient, inasmuch as the securing screw may be permanently molded to the knob in the process of its manufacture.

As shown, a screw 20 of ordinary construction is embedded in the material of the insulating knob and extends through the shank thereof in order to afford greater mechanical strength, as it thus acts as a reinforcing means in the body of insulating 75 material. The upper or head portion 21 of the screw is thus positioned in the body of the finger portion of the key knob and the insulating material will fill up the slot 22 in the head 21 of the screw (which is normally provided for a screw driver) so that the screw will therefore be securely and rigidly molded and held to the knob.

The projecting portion 23 of the screw shank is provided with screw threads 24 85 which are utilized to engage with the screw threads 25 in the hole 26 formed in the outer extremity of the key lever L when the knob has been mounted upon the screw lever as illustrated in Fig. 2. The exposed end of 90 the screw shank if desired may be hammered over to form a securing flange 27.

It is well known that the ease with which an operator can transmit is governed by the shape and proportions of the key knob, 95 namely, the diameter of the knob and the distance or height of the knob from the table, both of which contributes to a maximum transmitting speed. Not only have I brought about this proportion of key knob 100 diameter to height above table, but the above mentioned protective insulating shield is so placed as to act also as a rest and a firm stop for the finger tips. Thus the fingers are allowed to relax without loosing the necessary grip on the key. This condition not only increases the ease with which the key 105 can be manipulated but the endurance of the operator is also increased thereby.

The insulating material used in the construction of this invention may be of any suitable material of that nature, but I pre-

fer to use the insulating material which is known in the art as "electrose."

As changes of construction could be made within the scope of my invention, it is intended that all matter contained in the above description or shown in the accompanying drawings shall be interpreted as illustrative and not in a limiting sense.

Having now described my invention what I claim as new and desire to secure by Letters Patent is:

1. An insulating knob for telegraph keys consisting of a finger portion, a shank and an insulating shield extending a material distance radially from the shank and at a point adjacent the finger portion, the said shield forming an insulated finger rest and protector for the remaining inactive fingers of the hand of the operator.
2. A key knob of insulating material, having a finger portion at one end and a finger rest and protective insulating shield for the remaining inactive fingers of the hand of the operator, the said shield having a materially greater area than the said finger portion, and situated below and separated therefrom.
3. A key knob having a body portion of insulating material, a finger portion also of insulating material at one end thereof, and a protective insulating shield projecting a material distance from the body portion and adjacent to the said finger portion, the entire under surface thereof being provided with a series of concentric grooves and ribs to extend the area thereof.
4. A key knob consisting of a body portion of insulating material, a finger operating portion at one end thereof, a protective insulating finger rest and shield of materially greater area than the finger portion, projecting from the body portion, adjacent

to and below the said finger portion, the said finger rest and shield having on its under surface a series of concentric grooves and ribs, a metallic reinforcing element embedded within the central portion of the key knob and extending substantially therethrough centrally thereof and projecting from the body portion at one end, provided with means for attachment to a key lever, the upper end of the metallic reinforcement being provided with means for engagement with the insulating material of the knob to prevent its turning axially.

5. A key knob consisting of a body portion of insulating material, a finger operating portion at one end thereof, a protective insulating finger rest and shield of substantially greater area than the finger portion, projecting from the body portion adjacent to and below the said finger portion, the said finger rest and shield having on its under surface a series of concentric grooves and ribs, a metallic reinforcing element embedded within the central portion of the key knob and extending substantially therethrough centrally thereof and projecting from the body portion at one end, provided with means for attachment to a key lever, the metallic reinforcement being provided with means for engagement with the insulating material of the knob to prevent its turning axially.

In witness whereof I have hereunto set my hand at the borough of Manhattan, city, county and State of New York, this fifteenth day of January, 1918.

LOUIS STEINBERGER.
